UNITED STATES PATENT OFFICE.

A. HADLEY, OF LYNN, MASSACHUSETTS.

MACHINE FOR FILING SAWS.

Specification of Letters Patent No. 24,118, dated May 24, 1859.

To all whom it may concern:

Be it known that I, A. HADLEY, of Lynn, in the Commonwealth of Massachusetts, have invented an Improved Machine for 5 Filing Straight and Circular Saws; and I do hereby declare that the following is a full and exact description thereof, reference being had to the accompanying drawings, and to the letters of reference marked 10 thereon.

To enable others skilled in the art to which my invention belongs to make and use the same, I will proceed to describe its construction and operation.

15 Figure 1, of the drawings represents a perspective view of the machine when used for filing straight saws; Fig. 2, represents a perspective view of a circular saw mounted on a shaft.

20 *a*, represents a straight saw which is clamped between a plate *d*, and a rail *e*, by means of a set screw *c*, which screws through the end of an arm *b*, extending from the rail. The rail slides in grooves *f*, *f'*, in frame *g*; 25 the bottom of the frame has a slot through which the pawl *x*, works in combination with ratchet teeth in the under surface of the rail. A piece *i''', i''', j''', i*, is made with two arms *i''', i''',* which are pivoted to 30 the frame *g* at *h*, *h*, only one of these pivots being visible in the drawings. Two rods *f', f'*, are pivoted to staples extending from the under surface of the railframe *g*, at *g', g'*.

The whole combination of parts above described *a d c e b g i i''' i''' j''' f' f'*, can be removed from the machine or may be attached to it in the following manner. The lower ends of the rods *f', f'*, are passed into holes made through sleeves *i', i'*, and table 35 *o'*, and the pivot *i*, is passed into ring *k*, until the rim *j''',* rests against the upper surface of ring *k*, and the pawl *x*, is in contact with the ratchet teeth in the bottom of the rail *e*. The rail and railframe can now be 40 moved on pivots *h*, *h*, the rods *f', f'*, playing freely through the sleeves *i', i'*, and table *o'*. When the rail and railframe have been set at the desired inclination, they can be confined in their position by screwing up the set 45 screws *h', h'*, until their ends bear firmly against the rods *f', f'*, in the sleeves. The ring *k*, is permanently fastened to the table *o'*, by two supports *j, j*. The pawl *x*, is pivoted to the upper end of an arm *w*, and is held and pressed upward by a spring *y*, riveted to arm *w*. The lower end of the arm 50

w, is formed into a hub which is fastened to a shaft *s*, by means of a set screw (not shown in the drawings).

The shaft *s* (part of which is represented in the drawings as broken away) has its bearings in standards *v, v*, the rear end of the shaft carrying a crank *t*, and a connecting rod *u*, being pivoted to the lower end of the crank, while the other end of the connecting rod *u*, is jointed to a staple *d'*, which extends from the rear end of stirrup *e'*. The central part of this stirrup has a hole loosely fitting the shaft of a horizontal ratchet wheel *t''*, and a collar *v''*, slotted at *u''*, is fastened to the shaft of the ratchet wheel above the stirrup, by means of a set screw (not shown in the drawings). The top of the ratchet wheel shaft is pointed as seen at *l*, and the center line of the shaft is in line with the center of ring *k*. A pawl *k'*, is pivoted to the table *o'*, and is held against the teeth of the ratchet wheel by a spring *l'*. Another pawl *j'*, pivoted to the front part of the stirrup is also made to engage with the teeth of the ratchet wheel by means of a spring *m'*.

The front end of the stirrup can be lengthened or shortened by moving the slotted piece *n'*, in or out and then confining it by the set screw passing through the slot.

The play of the rear end of the stirrup is regulated by a screw *a'z*, which screws through a staple *b'*, fastened to table *o'*, the staple *d'*, bearing against the end of the screw *a'z*, in consequence of the tendency of a spiral spring *c'*, fastened at both ends to the staples *d'*, and *b'*. By screwing the screw *a'z*, in or out more or less play may be given the rear end of the stirrup.

The table *o'*, has slots *p'*, in its sides which fit over tongues *q'*, projecting from the horizontal portion *r'*, of the main frame of the machine, so that the table *o'*, may be moved in or out upon said tongues.

The upright portion *s', s'*, of the main frame is made with arches *t', t'*, forming parts of one circle, the arches being grooved on their inner sides as seen at *w'*.

The block frame *v'*, is rounded at the top and bottom at *u', u'*, so as to fit the circle of the arches, and has projections which correspond with the grooves *x''*, in the arches.

Slotted plates *z''',* are fastened one to the top part of the block frame and the other to the bottom part of it, set screws *s''',* passing through the slots in the plates *z''',* and

screwing into the arches t' , t'' , (only one plate z''' , and screw s'' being shown in the drawings).

It will be seen from the above that the 5 block frame v' , can play in the grooves w'' , and can be moved around its center, and can be confined in any position by means of the set screws s'' .

The inside of the block frame is provided 10 with two vertical grooves w' , one on each side, the grooves being slightly curved at the upper end, as seen at y''' .

A block y' , is provided with four friction rollers, one of which is seen at x' , which fit 15 into and move in the grooves w' .

The slotted end of a lever c'' , pivoted to the frame s' , at d'' , fits over a pin a'' , projecting from the block, and the other end of the lever c'' , is connected to a crank g'' , by 20 means of a rod f'' , and knuckle joint e'' . The crank g'' , is keyed to the end of driving shaft h'' , which has its bearings in staples w'' , w'' , fastened to frame s' , s'' ; the shaft may be driven either by means of 25 a handle attached to flywheel l' , or in any other suitable manner. A bevel pinion i'' , upon shaft h'' , takes into a bevel wheel j'' , which is provided with a pin k'' , projecting downward from a point near its periphery.

30 When the table o' , has been moved forward on the tongues q' , as far as it will go, the pin k'' , will strike the end n' , of the stirrup e' , once during one revolution of the bevel wheel j'' , moving this end of the 35 stirrup sidewise, more or less according to the adjustment of the piece n' . Of course the farther the piece n' , is made to project the longer will the pin k'' , be in contact with it and the greater will be the sweep 40 imparted to the end of the stirrup.

Two long screws z' , z'' , screw through a block y' , their ends supporting and turning in a bracket m'' .

Plates are fastened to the top and bottom 45 of the bracket which serve as bearings for a short vertical shaft n'' , to which a file q'' , is fastened by means of clamps and set screws r'' , o'' . A slotted wing p'' , extending from the top part of shaft n'' , in combination with a set screw screwing into the 50 top of the bracket m'' , serves to turn the file around the axis of the shaft n'' , so as to give the sides of the saw teeth more or less inclination.

55 When it is desired to file circular saws, the parts a , b , c , d , e , g , f , f' , i''' , i''' , j''' , i , are removed, and the shaft z'' , (upon which the circular saw y'' , is mounted as seen in Fig. 2,) is inserted between the

60 points m , and l , and the screw m , is turned down until it enters the little cavity in the end of the shaft z'' , the points m , and l , will then serve as pivots for the shaft z'' .

The screw m , passes through a block n , 65 which can be moved in a slot in the piece p ,

by means of an adjusting screw o . The piece p , extends from the upper end of a curved rod q , the lower end of which is firmly screwed into a standard r , fastened to table o' . By moving the block n , in the slot the inclination of the shaft z'' , and consequently the inclination or bevel of the teeth of the circular saw can be determined. A clamp a''' , is fastened to the lower end of shaft z'' , by means of a clamping screw b''' , the tooth c''' , of the clamp being inserted in the slot u'' , in the collar v'' , of the ratchet wheel t'' . Thus the shaft z'' , will be caused to turn with the ratchet wheel t'' .

The operation of the machine above described, is as follows: The table o' , either with the circular saw y'' , or with the straight saw a , and its appurtenances, is moved forward on the tongues q' , as far as it will go. The bevel of the saw teeth is then determined by either adjusting the circular saw shaft by means of block n , and screw o , or by setting the saw plate a , at the necessary inclination by means of rods f' , f'' , and set screws h' , h'' . By adjusting the block frame v' , in its circular ways w'' , so as to incline the file q'' , from the vertical line, the bevel of the saw teeth can be increased beyond the limits of the adjustment obtained by means of block n , and screw o , or rods f' , f'' , and set screws h' , h'' . Thus it will be seen the angle between the surface of the sawplate a , or y'' , and the centerline of file q'' , to wit the bevel of the saw teeth can be determined. The file q'' , is then moved toward the saw plate, by means of the screws z' , z'' , until the edge of the file engages with the edge of the saw plate. Before commencing the operation of filing the teeth, the file is also to be adjusted around the axis of shaft n'' , by means of the set screw and wing p'' , so as to cause the teeth to be filed more or less pointed. Now when the driving shaft is set in motion the crank g'' , will actuate the lever c'' , so as to impart a vertical reciprocating motion to the block y' , and to the file q'' , connected to the block, so as to cause the file to make incisions into the edge of the saw plate. After the whole length of the straight or the whole circumference of the circular saw, has been thus filed, the file may be advanced a little by means of the screws z' , z'' , so as to cut the teeth deeper, and so forth. As often as the block y' , arrives toward the end of its upward motion, the friction rollers x' , enter the curved portions y''' , of the grooves w' , so as to cause the block y' , and file q' , to move back from the edge of the saw plate. Simultaneously with this disengagement of the file from the saw plate, the pin k'' , strikes the end n' , of the stirrup e' , and causes the end of the stirrup to describe an arc around the center l , until the pin leaves the end n' , and the stirrup returns to its former position following the tendency 130

of the spiral spring c' . This motion of the stirrup causes the pawls j' , k' , to move the ratchet wheel t'' , the distance of one or more of its teeth, and operates also the device 5 d' , u , t , s , w , so as to cause the pawl x , to move the rail e , the distance of one or more of the ratchet teeth in the bottom of the rail, and thus move the saw plate a , a distance of one saw tooth. But if the circular plate y'' , 10 is in the machine instead of the straight plate a , the motion of the ratchet wheel t'' , causes the shaft z'' , to turn with it so as to turn the saw plate y'' , the distance of one saw tooth. During the time the saw plate 15 y'' , is thus advanced, the block y' , and the file commence their downward motion, and by the time the pin k'' , slips off the end n' , of the stirrup, the friction rollers x' , leave the grooves y''' , and the file engages again with 20 the edge of the saw plate and cuts the next tooth.

Having described my improved machine for filing straight and circular saws, what I claim therein as new and desire to secure by 25 Letters Patent, is:

1. Determining the bevel of the teeth of a straight saw by means of pivoting the frame g , (which supports the rail e , and saw plate a), at h , and hinging rods f' , f'' , to said 30 frame g , as seen at g' , g'' , and confining these rods in their relative position by set screws h' , h'' , constructed and arranged substantially as above described.

2. Determining the bevel of the teeth of a

circular saw by arranging the shaft z'' , of 35 the saw between two points l , and m , one of the points, m , being adjustable by means of a grooved piece p , block n , and set screw o , the whole being constructed and combined substantially as above described. 40

3. Determining the bevel of straight and circular saws, by combining the frame v' , with grooves x'' , forming arcs of a circle, in combination with clamp screws s'' , and slotted plates z''' , substantially as above described. 45

4. Holding the file by clamps r'' , r''' , set screws o'' , o''' , in combination with shaft n'' , set screw p'' , and bracket m'' , constructed and operating substantially in the manner 50 and for the purpose set forth.

5. The combination of the movable table o' , with the mechanism for supporting and moving the saws, constructed and arranged thereon as shown and described, whereby the 55 same machine can be quickly adapted for filing either straight or circular saws as set forth.

6. The combination of the mechanism for supporting and moving the saws, with the 30 mechanism for supporting and operating the file—constructed, arranged and combined as above described and for the purposes set forth.

A. HADLEY.
